UNITED STATES PATENT OFFICE.

FRANK M. LEE, OF CHICAGO, ILLINOIS, ASSIGNOR TO SULLIVAN MACHINERY COMPANY, A CORPORATION OF MASSACHUSETTS.

FORGING MECHANISM.

Application filed February 28, 1923. Serial No. 621,806.

My invention relates to forging mechanisms, and more particularly to forging mechanisms of a type especially adapted for use in the formation of channeled steels.

5 In the usual channeled gang there are provided steels which serve for the purpose of chopping and other steels which serve the purpose of leveling, the chopping steels projecting downward slightly further than the leveling steels and having their edges extending transversely of the channeled, practically at right angles to the path of movement of the gang during operation. The leveling steels have diagonally arranged 10 edges which do not project downward quite so far as the chopping steels, but which serve to level off and loosen the ridges left after the passage of the chopping steels. Various forms of dies have been devised 15 heretofore, but it has always been necessary in the employment of these dies for the sharpening of channeled steels to employ several sets of dies to secure the desired results, it ordinarily being necessary to make 20 a wholly distinct set for the diagonals from those used for the ordinary transverse or chopping steels.

An object of my invention is to provide 25 improved forging mechanism for the sharpening of implements of the type employed in channeled gangs. Another object of my invention is to provide improved die means whereby all the operations necessary for the formation of both the straight and diagonal 30 steels which go to make up a complete channeled gang may be executed. Other objects and advantages of my invention will hereinafter more fully appear.

In the accompanying drawings I have 35 shown for purposes of illustration two forms which my invention may assume in practice.

In these drawings,—

Fig. 1 is a side elevation of the die means 40 provided for the purpose of flattening the transverse and diagonal steels and tapering the former.

Fig. 2 is an opposite side elevation of 45 these die blocks showing the gaging and edge forming means.

Fig. 3 is a view similar to Figure 1, showing the means for gaging diagonal steels.

Fig. 4 is a front view of the dies shown in Fig. 3.

Fig. 5 is a view of a series of loose pieces 55 employed in the gaging of the transverse steels.

Fig. 6 shows a somewhat different form 60 of die blocks with a different form of diagonal gaging means.

Fig. 7 shows a clamping die and dolly used in the formation of diagonal steels.

Fig. 8 is a front view of the dolly.

Fig. 9 is a perspective of the die blocks 65 one of which is turned at an angle of ninety degrees from its normal position.

As it will in nowise increase the clarity of the disclosure to show the forging mechanism with which my improved dies are employed, I have not illustrated such machines and it will be understood that throughout the drawings of the forging dies the lower die is stationary, while the upper die is adapted to be reciprocated with light or heavy strokes so as to strike the work 70 or heavy strokes so as to strike the work 75 variable blows.

Noting the dies, and noting particularly first the construction shown in Figures 1 to 5, it will be observed that I have provided upper and lower dies 1 and 2 of 80 which, as stated, the lower die is stationary, while the upper die is reciprocated. The upper die will be observed at its left hand side in Figure 4 to be formed (see also Fig. 2), with a projection 3 which has a front 85 surface 4 arranged at an angle of approximately 45 degrees to the horizontal and, forward of the extremity of the surface 4, a downwardly facing, oppositely sloping surface 5 which makes a slight angle, herein 90 5 degrees, with the horizontal. At its right hand side, as viewed in Fig. 1, this die is provided with flattening and lateral edge forming inclined surfaces 7 and 8 respectively which intersect at 9 and which are at 95 their line of intersection slightly rounded off for fullering action to initially roughly reduce the size of the steel bar. The lateral edge forming means comprising the surface 8 and the surfaces on the cooperating blocks 28' or 35 is for roughly gaging the lateral edges of the steel. The lower die at its left hand side, as viewed in Fig. 2, is provided with an inclined surface 12 upon which a tool steel block 13 having a cutting edge 14 and a surface 15 arranged at 90 degrees to the surface 4 is secured by a heavy bolt 16. The edge 14 and portion 18 comprise

cutting edge forming means for forming the cutting edge of a steel. Forwardly of the cutting off block 12 there is a vertical wall 17 which constitutes the rear wall of a recess 18. This recess has a bottom wall 19 and into this recess there may be set, depending upon the gage desired, one or another of a series of gaging blocks 20, 21, 22 and 23 (see Fig. 5). The upper surface of these gaging blocks is arranged to make with respect to the horizontal an equal but opposite angle to the surface 5. At the other side of the die block 2 there is another flattening surface 26 which is oppositely inclined to the surface 7 and cooperates with that surface in the drawing out and flattening of a channeler steel. The surface 26 is carried up to a point opposite the fullering point 9 on the upper die 1 and then slopes away for a short distance as at 27. A recess 28 is formed to the rear of the point 27. The function of this recess will hereinafter be more fully described. In order to permit tapering the sides of the transverse steels, there may be used a block 28' whose top is oppositely sloped compared with the surface 8 to thereby allow the lateral edges of the steel to be formed, and which fits in the recess 28, but this block is ordinarily unnecessary as the flattening of the transverse steels seldom is such as to produce as great a width behind the edges as at the latter.

The mode of operation of the dies as so far described is as follows: A blank steel or a dull steel will be worked between the surfaces 7 and 26 when in a properly heated condition, the steel, if extremely dull, having its forward portion projected beyond the portions 9 and 27 to obtain a fullering action. After the steel has been tapered to the desired degree, a proper cutting edge is formed thereon by placing the extremity of the steel upon the edge 14 and causing the die 1 to strike the steel a sharp blow. Thereby a proper cutting edge is produced. To make the steel of the proper gage, it is next turned on edge and, if desired, may be tapered between the surfaces 8 and block 28', or simply the proper die block, 20-23, having been selected and placed in position, the front end of the steel is rested upon the block 20, 21, 22 or 23, which is in use, and the upper edge is struck by the surface 5, the dies being prevented by the portions 29 and 30 from coming together closer than the proper gage. The last operation will nearly always suffice.

A diagonal steel will be flattened in a manner similar to that described with reference to the flattening of the transverse steels. The gaging, however, cannot be accomplished by the surface 5 and block previously employed. I accordingly have provided an attachment 35 adapted to fit in the

recess 28 and providing at 31 an inclined surface adapted to support the lateral inclined surface of the diagonal steel and further providing as at 32 an overlying portion or lip adapted to catch the lower side of the diagonal steel and prevent twisting thereof as the upper side is struck by the surface 8. It will be noted that this loose piece is provided with recesses 33 which may be seated over pins 34 to hold the loose piece in position, the block 28' being obviously similarly held. As the angle of the surface 8 is not less than the taper of the transverse steels, it will be understood that the diagonal steels, when placed in the gang with the transverse steels, will be of the proper gage, it being understood further that the distance between the bottom of the recess in which the diagonal steel is received and the most remote point by which that steel can be engaged on the surface 8 is equal, when projected on a vertical plane, to the gage of a transverse steel. It will be understood that the diagonal steel having been flattened to the desired taper by the surfaces 7 and 26, may be rested upon the surface 31 and with its lower edge caught under the lip 32 and then struck by the surface 8 to produce the proper gage. Suitable clamping dies 39, of which one is shown in Figure 7, may grasp the diagonal steel and hold the same while a dolly 40 having a diagonally arranged groove 41 for the purpose of sharpening the diagonal steels is used.

In the form of my invention shown in Figure 6, instead of cutting away the lower die and forming a recess 28 and using the loose piece 35, the lower die is made to correspond in shape to the upper die at its right hand side and when the gaging operation is to be performed on diagonal steels, the mechanism including the parts 31, 32, etc. is mounted by means of a saddle-like support 42 upon the lower block 2. The mode of operation of this form of my invention is the same as in the preceding cases.

While I have in this application specifically described two forms which my invention may assume in practice, it will be understood that these forms of the same are shown for purposes of illustration and that the invention may be modified and embodied in other forms without departing from its spirit or the scope of the appended claims.

What I claim as new and desire to secure by Letters Patent is:

1. In a forging machine, relatively stationary and moving blocks having at opposite sides thereof swaging surfaces and edge forming means being so disposed that a steel worked upon by the swaging and forming means will lie in separate vertical planes.
2. In a forging machine, relatively sta-

tionary and movable die blocks having at opposite sides thereof, of a line transverse thereto swaging surfaces and lateral edge forming surfaces, the longitudinal axes of 5 said surfaces being substantially in alignment.

3. In a forging machine, a stationary die block, and a relatively movable die block, said blocks having at the same sides thereof 10 and opposite to each other gaging surfaces and cutting off surfaces, said latter surfaces being operable independently of said other surfaces when working upon a normal size steel.

15 4. In a forging machine, a stationary die block, a relatively movable die block, said blocks having at the same sides thereof and opposite to each other gaging means and cutting off surfaces, one of said blocks being 20 recessed and adapted to receive variable gage blocks seating in said recess.

5. In a forging machine, a relatively stationary die, a relatively movable die, said movable die having a gaging surface formed 25 thereon at an incline and said stationary die providing an inclined work supporting surface adapted to support a channeler steel in a position with the edge thereof at an angle to the horizontal.

30 6. In a forging machine, a relatively stationary die, a relatively movable die, said movable die having a gaging surface formed thereon at an incline and said stationary die providing an inclined work supporting surface adapted to support a channeler steel in a position with the edge thereof at an 35 angle to the horizontal, and an overlying portion adapted to hold the lower edge of said steel against twisting.

40 7. In a forging machine, gaging dies comprising a die having a gaging surface formed thereon, a die having a recess, and means whereby die blocks of different heights and having surfaces adapted to co- 45 operate with said first mentioned gaging surface to gage a steel may be inserted in said recess.

50 8. In a forging machine, die blocks having flattening surfaces on one side of a transverse plane and lateral edge forming surfaces on the opposite side thereof whereby a steel may be passed longitudinally from one surface to the other.

55 9. In a forging machine, die blocks having flattening surfaces on one side of a transverse plane and lateral edge forming surfaces on the opposite side thereof, and fullering means at the junctions of said surfaces.

60 10. In a forging machine, a stationary member providing a die supporting surface, a movable gaging die reciprocable in a path at an angle to said surface, the limit of said path toward said surface being fixed, and 65 die blocks of different heights disposable

upon said surface whereby different gages may be accurately imparted to different blanks.

11. In a forging machine, a stationary member, a movable gaging die reciprocable 70 in a path at an angle to said surface, the limit of said path towards said surface being fixed, and means whereby die blocks of different heights may be disposed upon said stationary member to accurately impart to 75 different blanks different gages, said means having a plurality of surfaces disposed in different planes and adapted to engage said member.

12. In a forging machine, gaging dies 80 movable towards each other, the limit of said movement being fixed, and means whereby die blocks of different heights are adapted to be carried by one of said dies to accurately impart to different blanks differ- 85 ent gages.

13. In a forging machine, a stationary member providing a die supporting surface, a movable gaging die reciprocable in a path 90 at an angle to said surface, the limit of said path toward said surface being fixed, and means whereby die blocks of different heights are disposable upon said surface whereby different gages may be accurately 95 imparted to different blanks, said means including gage block positioning means that is common to all of said gages.

14. In a forging machine, a stationary member providing a die supporting surface, a movable gaging die reciprocable in a path 100 at an angle to said surface, the limit of said path toward said surface being fixed, means whereby die blocks of different heights disposable upon said surface whereby different gages may be accurately imparted to different blanks, and surface engaging means cooperating with said gages including means that is common to all of said gages.

15. In a forging machine, relatively mov- 110 able dies, a gaging surface on one of the same, and common means whereby gaging means of different types are adapted to be carried by the other thereof to present co- operating gaging surfaces to said first mentioned surface.

115 16. In a forging machine, die blocks having inclined swaging surfaces on one side thereof, and fullering means disposed substantially at one extremity of said surfaces.

17. In a forging machine, relatively mov- 120 able dies, a gaging surface associated therewith, and means whereby a plurality of means used during gaging of steels of different types are adapted to cause said different steels to be gaged by said surface.

125 18. In a forging machine, relatively mov- able dies, a gaging surface associated therewith, and means whereby a plurality of means used during gaging of steels of dif- 130 ferent types is adapted to cause said dif-

- ferent steels to be gaged by said surface, and common means for engaging any of said different types of gaging means.
19. An article of manufacture comprising a steel gaging element having a plurality of similarly transversely angularly disposed surfaces which are adapted to engage a plurality of steel surfaces adjacent one edge thereof while a gaging operation is being performed thereon.
20. An article of manufacture comprising a gaging element adapted to support a steel during a gaging operation thereon, and having means for preventing turning of said steel during said operation.
21. In a forging machine, die blocks having gaging means comprising a gaging surface, and means to angularly support a steel during a gaging operation thereon and to prevent turning thereof during said operation.
22. Forging machine die blocks having means to support a steel during a forging operation comprising a member having a transversely angularly disposed slot to receive the lateral edge of the steel.
23. In a forging machine, relatively mov-

able dies, gaging means associated therewith including a gaging surface, and means whereby a plurality of different surfaces may be disposed below said other surface to allow said first surface to be common to the gaging operation on a plurality of different types of steels.

24. In a forging machine, relatively movable dies, gaging means associated with said dies including means whereby a plurality of means are adapted to support different steels in different angular positions, and a common surface also associated with said dies to cooperate with said plurality of means to perform a gaging operation on said steels when held in any of said positions.

25. In a forging machine, relatively movable dies, a gaging surface on one of the same, means whereby a plurality of gaging blocks of different heights may cooperate with said surface, and means common to the use of any one of said gaging blocks to position longitudinally a steel being gaged.

In testimony whereof I affix my signature.

FRANK M. LEE.

Certificate of Correction.

It is hereby certified that in Letters Patent No. 1,590,583, granted June 29, 1926, upon the application of Frank M. Lee, of Chicago, Illinois, for an improvement in "Forging Mechanisms," errors appear in the printed specification requiring correction as follows: Page 1, line 93, after the word "with" insert the words *swaging or*; page 3, line 2, claim 2, strike out the word and comma "thereof,"; and that the said Letters Patent should be read with these corrections therein that the same may conform to the record of the case in the Patent Office.

Signed and sealed this 28th day of September, A. D. 1926.

[SEAL.]

M. J. MOORE,
Acting Commissioner of Patents.
